UNITED STATES PATENT OFFICE.

MICHAEL J. SASGEN, OF CHICAGO, ILLINOIS, ASSIGNOR TO GRAND SPECIALTIES COMPANY, OF CHICAGO, ILLINOIS, A CORPORATION OF ILLINOIS.

DOORSTOP.

Application filed February 6, 1922. Serial No. 534,287.

To all whom it may concern:

Be it known that I, MICHAEL J. SASGEN, a citizen of the United States, and resident of Chicago, in the county of Cook and State 5 of Illinois, have invented certain new and useful Improvements in a Doorstop, of which the following is a specification.

My invention relates to an improved door stop and has special reference to a stop 10 particularly adapted for outside doors such as garage doors.

The object of my invention is to provide a stop of very simple and cheap construction 15 preferably comprising but two pieces, a base and a strut adapted to be attached to the lower part of the door. The strut is adapted to be dropped into an inclined position and to contact with the roadway. The base is formed to provide yielding arms or lugs between which the strut is adapted to be firmly held in non-operative position. The strut 20 may be provided with various forms of ends or shoes for contacting with the surface of the roadway. The roadway with which the 25 strut contacts is frequently made of cement and I have found it advisable to provide contacting shoes for the lower end of the strut which are adapted to enlarge the contacting surface of the strut and in any case the 30 strut is provided with a single point or a plurality of teeth or V-shaped edges for contacting with the roadway.

My invention will be more readily understood by reference to the accompanying 35 drawings forming part of this specification, and which:

Figure 1 is a front view of the device shown in position upon a door;

Figure 2 is a side elevation of the device;

Figures 3 and 4 are horizontal sectional 40 views on the lines 3-3 and 4-4 respectively of Figure 1;

Figure 5 is a plan view of a bracket blank before the ears are bent up;

Figure 6 is a fragmentary side view of a 45 modified form of strut;

Figure 7 is a longitudinal sectional view on the line 7-7 of Figure 6; and

Figure 8 is a view similar to Figure 6 50 showing a rubber pad for contact with the floor.

My device comprises a bracket 1 adapted to be secured to a door near the lower end thereof and a strut member 3 pivotally connected to or mounted upon the bracket and

adapted to be dropped into the position shown at dotted lines in Figures 1 and 2 where it acts as a strut to prevent the door from swinging in one direction, or to be raised out of operative position into vertical 60 position and yieldingly held in inoperative position by suitable ears carried by the plate 1.

Preferably the plate 1 is made of sheet metal and the strut 3 is made from a strip of 65 bar metal. As best shown in Figure 5 the base is first stamped out of sheet metal in somewhat triangular form having at its upper part arms 4 which are adapted to be formed up, as best shown in Figure 3, to provide 70 parallel spring arms between which the strut 3 is adapted to be engaged and held as shown in Figure 2. The body of the base plate is provided with two portions 5 which are severed at their outer edges from the 75 body of the plate and are adapted to be bent up in parallel relation as best shown in Figure 4 to form ears 6 between which one end of the strut 3 is adapted to be received and pivotally secured by a rivet 7. The 80 base is provided with suitable screw holes 8 for receiving fastening screws by which the base can be secured to the door 2.

The free end of the strut 3 may take different forms or be provided with different 85 kinds of shoes for contact with the floor or with the roadway, if the device is used on a garage door. For the latter use I prefer to provide the lower end 9 of the strut with V-shaped teeth 10 which are 90 adapted to dig into or engage the ground or the cement over which the door swings the device, in such instance, being arranged on the inner face of the door and being adapted to be used to hold the door from 95 swinging shut. The door in this instance, of course, is an outwardly opening door.

The end 9 of the strut is curved symmetrically in the direction of swinging motion of the strut and is provided with a plurality of the teeth 10. This form is particularly useful for engagement with a cement floor as the strut will engage with the floor and as the door starts to swing the strut will tend to swing slightly toward the 105 door and cause the teeth to engage the cement with great force.

A particularly advantageous feature of this form of strut lies in the symmetrical formation of its free end whereby which 110

ever way it is assembled with the base it will present teeth to the floor when dropped to engaging position.

For some purposes, it is desirable to widen the engaging surface of the strut with the floor and in Figures 6 and 7 I have shown the strut as provided with a shoe 12 which is pivotally mounted on the lower end of the strut 3 by means of a rivet 13. The shoe as best shown in Figure 7 has a contacting surface which is much wider than the strut bar and is provided with transverse teeth 14 for engagement with the floor. The shoe 12 can rotate to some extent on the bar but is prevented from rotation out of engagement with the floor by means of the engagement of the shoe with the lower corner 15 of the bar.

In Figure 8 I have shown a shoe 16 similar to the shoe 12 but provided with a rubber pad 17 for contact with the floor and the rubber pad is provided with transverse ridges 18 similar to the teeth 14 on the shoe 12. I find that this rubber padded end on the strut is useful on the device when applied to doors swinging over finished floors.

I do not herein specifically claim the base with the two pairs of struck up lugs, such being claimed in my companion application Serial Number 587,333.

As many modifications of my invention will readily suggest themselves to one skilled in the art, I do not limit or confine my invention to the specific details of construction herein shown and described.

I claim:

1. In a device of the kind described, a

strut adapted to be pivotally mounted at one end to swing up and down, the free end of the strut provided with a yielding gripping surface curved in the direction of swinging movement of the strut and said surface provided with transversely extending V-shaped ribs.

2. In a device of the kind described, a flat strut adapted to be pivoted at one end to swing up and down edgewise, a shoe on the free end of the strut, the shoe provided with a gripping surface extending beyond the flat faces of the strut, and curved in the direction of the swinging movement of the strut, as and for the purpose specified.

3. In a door stop, a sheet metal base adapted to be secured to a door, the sheet metal base provided with two pairs of struck-up lugs, one pair above the other, a flat metal bar strut adapted to be pivoted between the lower pair of lugs to freely swing up and down, the upper pair of lugs being formed to permit the body of the strut to be forced between them and to be engaged by a yielding pressure for holding the strut in an inoperative position, the free end of the strut being curved and formed with V-shaped teeth for engagement with a roadway, said free end being symmetrical in relation to its edges so as to be capable of presenting the engaging teeth to the roadway regardless of the assembled relation of the strut and base.

Signed at Chicago, Illinois, this 2nd day of February, 1921.

MICHAEL J. SASGEN.
